UNITED STATES PATENT OFFICE.

ALFRED CLIFFORD BROCK, OF FAZAKERLEY, LIVERPOOL, ENGLAND.

APPARATUS FOR MAKING MOLDS FOR CASTING METALS.

No. 893,137.

Specification of Letters Patent.

Patented July 14, 1908.

Application filed June 10, 1907. Serial No. 378,210.

To all whom it may concern:

Be it known that I, ALFRED CLIFFORD BROCK, a subject of the King of Great Britain and Ireland, residing at Fazakerley, Liverpool, in the county of Lancaster, England, whose post - office address is 38 Second avenue, Fazakerley, Liverpool, in the county of Lancaster, England, have invented certain new and useful Improvements in Apparatus for Making Molds for Casting Metals; and I do hereby declare the following to be a full, clear, and exact description of the invention, such as will enable others skilled in the art to which it appertains to make and use the same.

This invention relates to that class of machines which are automatic, or semi-automatic, in their nature, and particularly to the means whereby molds or parts thereof may be rammed or packed with sand and similar material.

This invention consists in the novel construction and combination of the parts hereinafter fully described and claimed.

In the drawings, Figure 1 is a front view of the machine. Fig. 2 is a side view of the machine. Fig. 3 is a detail side view, and Fig. 4 is a partial plan view, of the flat ramming platen with vent pins. Fig. 5 is a detached side view, and Fig. 6 is a plan view, of one of the peg ramming platens. Fig. 7 is a longitudinal section, and Fig. 8 is an end view, of the axle which supports the platens. Figs. 9 and 10 are end views of the valve controller. Fig. 11 is a detail view showing three peg rams.

In constructing a machine in accordance with these designs I make a main frame of the desired size, shape and arrangement by which the movable and other parts herein-after described are held and operated in desired position and direction. This main frame as shown in the drawings is preferably composed of a base portion *a* rectangular in contour when seen in plan view on which is erected a standard *b* rigidly fastened at its bottom end to the base *a* and supporting at its upper end the steam cylinder *c* with its valve chest *d*. This steam cylinder is situated immediately over and in line with a turn-over table *e* and is provided with a reciprocating piston *f* movably mounted therein whose piston rod *g* carries rigidly attached thereto a platen supporting frame *h*. This frame has movably mounted therein one or more sand ramming devices. In Figs. 1 and

2 this frame is shown carrying three of these ramming devices, *i*, *j* and *k*, *i* and *j* being peg ramming platens and *k* a flat ramming platen. These platens are supported by the hollow shaft or axle *L* shown in sectional elevation in Fig. 7 which is rotatably mounted in the frame *h*. Any one of these platens *i*, *j* or *k* can instantly be revolved into ramming position when the locking pawl No. 1 is lifted which is carried by the frame *h* and falls into notches so arranged and provided in the disk 60 2 which is a fixed part of the axle *L* that any particular platen can be held immediately over and in line with the table *e* which carries the molding box and patterns. The operation of the piston *f* thus moves up and down in a vertical direction the frame *h* with its various ramming devices hereinbefore referred to as the combination ramming head. 75 To limit and regulate the vertical reciproca-tion of this combination ramming head the controller shown in Figs. 1, 9 and 10, is pro-vided, consisting preferably of a frame or standard *m* used as a support for the hand 80 lever *n* and the hand wheel *o*. The lever *n* and the wheel *o* are rigidly fastened to spin-dles 3 and 4 respectively. These spindles being in gear with each other by means of toothed wheels not shown thus if the hand 85 wheel is revolved motion is transmitted through the geared wheels and their spindles to the hand lever likewise if the hand lever be moved the hand wheel is revolved. The tail end of the hand lever *n* is connected by 90 suitable rods 5 and cranks 6 with regulating lever *p* of an automatic valve operating de-vice *q* shown in side elevation Fig. 2. This valve device consists preferably of a sleeve 7 which has slidably mounted therein the 95 plunger 8 one end of which is pivotally at-tached to the platen frame *h* of the combina-tion ramming head. The sleeve 7 also car-ries cast or rigidly attached to it the ears or lugs 9 and 10. The regulating lever *p* is 100 pivotally mounted on the pin 11 carried by the standard *b*. One end of this lever is piv-otally attached to lug 10 of the sleeve 7 while the other end is similarly attached to the connecting rod 12. The lug 9 of the 105 sleeve 7 is suitably connected by means of a rod 13 to one end of the lever 14 which has its other end pivotally attached to the stand-ard *b*. Situated and suitably attached be-tween the ends of the lever 14 is the valve 110 rod 15 which operates the valve of the valve chest *d*. Thus any movement of the recip-

roating piston *f* is communicated by the means mentioned to the valve rod 15 and consequently to the valve.

An automatic movement being so established between piston *f* and its valve it becomes desirable to limit and regulate such movement so as to obtain a decreased or increased stroke of the said piston and to further control such movement as to arrest and hold the piston in desired position. For such a purpose the before mentioned regulating lever *p* is provided, which is operated from the controller. Referring again to this controller it will be seen that any movement of the hand lever or hand wheel is communicated to the regulating lever *p* which forming as it does a movable fulcrum for the valve device *q* conveys this movement to and by such device through the lug 9 and the further means hereinbefore mentioned to the valve. Thus the valve is under the operator's control and so regulates and controls the reciprocation of the combination ramming head. The hand lever *n* is limited in its movements by the sector 16 which determines the highest and lowest positions of the ramming head. The hand wheel *o* has rigidly attached to its spindle the disk 17 which has notches provided around its circumference into which the movable pawls 18 are flexibly held by the spring 19 the purpose of such arrangement being hereinafter more fully described.

Referring to Figs. 1 and 2 it will be seen that two peg ramming platens *i* and *j* have been provided. The object of this is that one platen may have rams adjusted to conform to the contour of the top half of a pattern while the other platen has rams adjusted to conform to the contour of the bottom half when each half pattern is dissimilar, so that *i* may be called a cope peg ramming platen and *j* a drag peg ramming platen. Figs. 6 and 5 show one of these platens in plan and elevation. It consists principally of a plate 20 in which are a number of screw tapped holes 21 to suit the screwed shank ends of the peg rams as shown in Fig. 11. This plate is rigidly attached to the brackets 22 which clip and are movably mounted on the eccentric portions of the spindles 23 and are sustained by the collars 24. Referring to the axle *L* shown in Fig. 7 these spindles are shown rotatably mounted in thrust bearings 25 which are rigidly attached to the axle *L*. The spindles with their eccentric portions are rotated by means of bevel toothed wheels 26 in gear with similar wheels 27 which are rigidly carried by a shaft 28 journaled in the axle *L*. This shaft may be rotated by means of a flexible shaft from any suitable source of power or by an electric motor, or by the mechanism shown in Fig. 8 which consists principally of a ratchet wheel 29 rigidly mounted on the shaft 28 and

a lever 30 loosely mounted on the same shaft which lever carries a loosely mounted pawl 31. The outer end of this lever is pivotally attached to a rod 32 which has its fulcrum in the fixed standard *b*, thus the vertical reciprocation of the combination ramming head results in a movement of the lever 30 whose pawl engages with the teeth of the ratchet wheel and rotates the shaft 28 which through the means described imparts a horizontal motion to the peg ramming platens. Having now shown how the peg ramming platens have a horizontal movement simultaneously with their vertical movements it will be seen how the rams with their downward movements ram the sand in a downward direction and with their horizontal movements reach each and every portion of the mold and further pack the sand under the molding box bars and any projecting pieces which may be on the pattern.

Fig. 3 shows the perforated flat ramming platen *k* with its adjustable vent pin head. It consists principally of a plate 33 rigidly attached to the axle *L*. Like the peg ramming platens *i* and *j* it can be instantly revolved into ramming position and used to flat ram the mold. For venting the mold the vent pin plate 34 shown in elevation, Fig. 3, is provided and mounted in the flat platen frame immediately behind the perforated platen 33. This vent pin plate is preferably mounted on guide pins 35 rigidly attached to the axle *L* and the perforated platen 33 and is provided with a plurality of vent pins 36 preferably screw threaded so as to be adjustably mounted in such plate. For holding this movable vent pin plate in and out of venting position the lock nuts 37 are provided which are adjustable along the screw threaded supports 38.

Further portions of the machine consist of the before mentioned table *e* shown in Figs. 1 and 2 used for fixing the patterns *r* to and for supporting and turning over the molding boxes *s*. In the molding box *s* slotted guide pins 39 are shown which slots receive cotters which firmly hold the molding box to the table while being turned over. To allow of this turning over the table is supported by the spindles or axles 40 which are rotatably mounted in the journals of the plungers 41. These plungers are slidably mounted in the plunger guides 42 and are each provided with toothed racks not shown which are in gear with and operated by toothed pinions slidably keyed on a key-wayed shaft 43. This shaft has slidably keyed on it a worm-wheel gearing with a worm operated by the hand wheel 44, thus the operation of the wheel moves the plunger 41 and consequently the table *e* in a vertical direction. Rigidly attached to one of the axles 40 is the capstan wheel 45. This is used for turning the table over on its axles 40. A locking disk 46 is

also provided which allows of the table being locked in a horizontal direction by means of a pawl 47 which falls into suitable notches provided in the disk 46.

5 The plunger guides 42 are each adjustable on the base plate *b* being preferably attached thereto by means of **T** headed bolts sliding in **T** shaped grooves provided in the base plate *a*. Thus the pinion and worm wheel not 10 shown being slidably keyed on the key-wayed shaft 43 allow of this lengthwise adjustment of the plunger guides without interfering with the mechanism for raising or lowering the table *e*.
 15 Provision is made for locking the table at its correct height by means of the peg 48 which is slidably mounted in a hole drilled through the plunger guide 42 and so arranged that half the circumference of the pin shall 20 fit in a suitable groove turned in the plunger and the other half in the plunger guide at the point of intersection of the groove in the plunger with the drilled hole of the plunger guide. The purposes of these details will be 25 more fully set forth in the description of the operation of the machine.

Referring to the frame *h* of the combination ramming head shown in Figs. 1 and 2, it will be observed that rods 49 are attached 30 to it at their lower ends and are movably mounted in brackets 50 carried by the standard *b*. Springs 51 are provided attached to either side of the brackets 50 and serve as 35 cushions for the ram frame should it get beyond control.

The operation of the machine is as follows:— The patterns to be molded are fastened down to the table *e* of the machine and if split patterns are used, as shown at *r*, that is patterns 40 which are split along their joint lines for convenience of molding, one portion of the pattern is fixed on one side of the table and its other portion fixed in alignment with it on the opposite side of the table. The table *e* is 45 raised by turning the hand wheel 44 to its correct height for ramming purposes indicated when the peg 48 slips in the groove provided for it in the plunger 41 which peg thus locks it. Suitable peg rams are screwed into 50 the platens *i* and *j* and are adjusted to conform with the shape and contour of the patterns used, care being taken that the peg rams are clear of the patterns and the table, when the combination ramming head is at 55 the lowest point of the stroke. These peg rams must also be arranged in such a manner that ample clearance is provided for them between portions of the pattern and the molding box and its bars, on account of their 60 horizontal movement. Having so adjusted the rams and tightened their lock nuts the combination ramming head is lifted and sustained in its highest position by pushing over the hand lever *n* of the controller to the position *t* of the sector 16 shown in Fig. 9, such 65

operation admitting steam to the under side of the piston *f*. A molding box *s* is placed on the table *e* and over the patterns *r* and is fastened down by cotters driven through the slots of the guides pins 39. This box is now 70 filled with sand, or a frame may be placed on it to provide an amount of sand which shall be sufficient to fill the molding box when such sand is in a compressed state. The hand lever *n* is pulled over to the position *u* of 75 the sector 16 and the machine then commences to automatically ram at its full stroke. As the mold is being rammed it is desirable to vary or decrease the stroke and this is accomplished by turning the hand wheel *o* of 80 the controller. In varying the stroke, in carrying out this invention, the length of the stroke may be allowed to remain constant, and the piston may be caused to reciprocate in a different part of the cylinder, so that 85 the peg rams do not descend so far, or the stroke of the piston may be shortened to make the peg rams descend to the required point. As hereinbefore mentioned a disk 17 is provided immediately behind the hand 90 wheel *o* and is rigidly attached to the same spindle. This disk having notches around its circumference with which the spring pawls 18 engage, offers a flexible resistance to the rotation of the hand wheel *o* and so enables the operator, as the mold becomes rammed course by course, to rotate the hand wheel, notch by notch of the disk 17 and so to gradually decrease the stroke of the ramming head until the mold is fully peg rammed. 100 If the rotation of the hand wheel *o* be continued in the same direction throughout its full number of revolutions the hand lever *n* moving gradually in the sector finally reaches the position *t* from whence it first started and 105 thus the ram is again being held in its highest position. The flat ramming platen *k* is now brought into ramming position, and if venting is required, the vent plate 34 with its vent pins 36 is suitably adjusted. The top 110 of the mold is now evened up and a scattering of sand thrown on. To flat ram the mold the hand wheel *o* is gradually rotated in a direction which reciprocates the ramming head through its shortest stroke and 115 gradually increases such stroke notch by notch of the disk 17 until the flat platen touches and finally flat rams and vents if necessary the mold. The catch or pawl 47 is now released and the mold, table and patterns are turned completely over by the capstan hand wheel 45. The catch 47 falls into a notch in the locking disk 46 and locks the table horizontally in its inverted position. 120 The table *e* is now lowered until the molding box and its mold is supported by a bogie carriage 52. The cotters of the guide pins 39 are released and the table raised thus lifting with it the patterns from out of the mold 125 and leaving that half mold complete or ready 130

for coring which is then taken away on the bogie carriage. A similar operation is performed for the other half mold and the requisite top and bottom parts are thus made 5 for the complete mold.

What I claim as my invention and desire to secure by Letters Patent is:—

1. In a molding machine, the combination, with a ramming platen, and means for reciprocating it; of a series of peg rams projecting from the face of the said platen, each peg ram being adjustable by hand independent of the others, and means for securing the said peg rams rigidly to the said platen so that 10 they cannot slide up or down independent of it.
2. In a molding machine, the combination, with a horizontal ramming platen, and means for reciprocating it vertically; of a series of 15 peg rams projecting from the face of the said platen, and driving mechanism operating to move the said platen and rams periodically in a plane parallel to the face of the said platen.
3. In a molding machine, the combination, 20 with a ramming platen provided with a series of holes, and means for reciprocating the said platen; of a series of peg rams adjustable by hand in the said holes and projecting from the face of the said platen, and means for 25 securing the said peg rams rigidly to the said platen so that they cannot slide up or down independent of it.
4. In a molding machine, the combination, 30 with a horizontally ramming platen, and means for reciprocating it vertically; of a series of peg rams carried by the said platen, and driving mechanism operating to gyrate the said platen and rams constantly in the same direction and in a plane parallel to the 35 face of the said platen.
5. In a molding machine, the combination, 40 with a horizontal ramming-platen, and means for reciprocating it vertically; of a series of rams carried by the said platen, and driving 45 mechanism operating intermittently and between the down strokes of the platen to slide the said platen and rams horizontally so that the rams operate on different spots at each successive down stroke.
- 50 6. In a molding machine, the combination, 55 with a flat ramming platen provided with perforations, and means for reciprocating the said platen; of a removable plate supported behind the said platen, and a series of vent-forming pins secured to the said plate and projecting through the perforations of the 60 said platen.
7. In a molding machine, the combination, 65 with a supporting frame, and means for reciprocating it; of an axle revoluble in the said frame, locking devices for securing the said axle to the said frame in different positions, ramming platens carried by the said axle, and adjustable peg rams projecting from the 70 faces of certain of the said platens.
8. In a molding machine, the combination, 75 with a supporting frame, and means for reciprocating it; of an axle revoluble in the said frame, locking devices for securing the said axle to the said frame in different positions, ramming platens provided with peg rams and supported by the said axle, and driving mechanism operating to move the said platens and rams periodically in planes parallel to the faces of the respective platens.
9. In a molding machine, the combination, 80 with a sand ramming device, and a fluid pressure motor for reciprocating it provided with a piston-rod and a regulating valve; of lever mechanism for operating the said valve automatically from the said piston-rod, and means for adjusting the said lever mechanism by hand to vary the stroke of the said motor.
10. In a molding machine, the combination, 85 with a sand ramming device, and a fluid pressure motor for reciprocating it provided with a piston-rod and a regulating valve; of a pivoted lever provided with a fulcrum pin, means for adjusting the said lever to vary the position of the said fulcrum pin, and lever 90 mechanism pivoted to the said fulcrum pin and operatively connecting the said valve with the said piston-rod.

In testimony whereof I affix my signature, in presence of two witnesses.

ALFRED CLIFFORD BROCK.
